UNITED STATES PATENT OFFICE.

CARL LEHR, OF HOMBOK, AUSTRIA-HUNGARY.

MACHINE FOR MAKING WIRE TACKS.

1,174,875.

Specification of Letters Patent.

Patented Mar. 7, 1916.

Application filed April 24, 1913. Serial No. 763,459.

To all whom it may concern:

Be it known that I, CARL LEHR, a citizen of Austria-Hungary, residing at Hombok, Moravia, Austria-Hungary, have invented 5 certain new and useful Improvements in Machines for Making Wire Tacks; and I do hereby declare the following to be a full, clear, and exact description of the invention, such as will enable others skilled in the 10 art to which it appertains to make and use the same.

This invention relates to new and useful improvements in machines for making tacks from a continuous wire.

15 It is the object of my invention to construct a machine of the above class which shall be especially adapted for producing strong, uniformly shaped, burless, sharp-pointed shoe-tacks.

20 With this object in view my improved machine consists in the novel combination of the following elements: first, a heading punch coöperating with two snugly closing holding dies clamping with semicircular 25 grooves the wire beneath the head to be formed, second, four pressing dies giving to the lower part of the blank a tapering, square shape, and third, two cutting dies independent of the holding and pressing 30 dies and shaping and cutting the end of the blank.

In order that my invention may be properly understood and readily carried into effect, I have hereunto appended two sheets 35 of drawings, of which—

Figure 1 is a plan of the machine embodying my invention. Fig. 2 is an enlarged fragmentary front elevation showing in particular the open holding dies and the 40 pressing dies. Fig. 3 is a like elevation with the cutting dies in front of the parts shown in Fig. 2. Fig. 4 is a section on line $x-x$ of Fig. 2. Fig. 5 illustrates a tack produced by my improved machine.

45 Referring to the drawings by reference characters, 1, 2, 3, and 4 denote the four pressing dies. 9 and 10 denote the holding dies. 20 and 21 indicate the cutting-dies, and 22 indicates the heading punch. The driving shaft 23 is provided at its outer end with an eccentric 24, which through suitable mechanism operates the sliding feed block 25. The feed block comprises the fingers 26, 27 gripping and feeding the wire 28 in 50 the known manner in between the pressing dies. In front of the block 29 there are

mounted the plates 7 and 8. The plate 8 is fast and accommodates in guides the dies 1 and 3, while the plate 7 accommodating the dies 2 and 4 is moved through the link 30 and the lever 6 pivoted at 31 from the cam-disk 5 keyed on the driving-shaft 23. The working faces of the four pressing-dies form a tapering square hole the cross-section of which diminishes as the plate 7 is moved 60 inward. The construction and operation of the coacting four pressing dies is well known in the art and needs no further description. The pressing-dies are held in their guides by the covers 12, 13. The inner edges of 65 these covers form a dove-tail guide 18 for the holding dies 9, 10. The holding-dies have in their end-planes semicircular grooves 33 of a diameter corresponding with the 70 diameter of the wire of which the tacks are 75 made. The position of the die 9 may be adjusted by the set-screw 19 on the fast plate 8. The die 10 is connected by its shank 17 with the lever 15 pivoted at 34 to which motion is imparted by the cam 35 of the 80 disk 5 and which is held in contact with the disk 5 by the spring 32. Pivotedly mounted at 36, 37 are the two-armed levers 38, 39 actuated by the cams 40, 41 on the driving shaft 23 and carrying at their front ends 85 the set-screws 42, 43 for the cutting and pointing dies 20, 21, the working ends of 90 which are suitably notched and coöperate to cut the blank from the wire and to form a tapering lance shape or a pyramidal point. 95 The cutting dies 20, 21 are adjustably fastened on the upper ends of the levers 44, 45 pivoted at 46, 47 respectively and connected at their lower ends by the spring 48. The shank 49 of the header 22 guided in the 100 axial line of the machine is normally held away from the clamping dies by a cam 50 of the driving shaft entering into a slot 51 of the header shank. A strong wooden spring 52 forces the header against the holding dies as soon as the cam 50 leaves the slot 51 of the shank 49.

The operation of the machine is as follows: The wire is fed in the pressing dies and clamping dies as to project with its end 105 from the latter. The pressing dies come according to the shape of the cam-disk 5 once or twice into action to form the square tapering lower part a of the shank of the tack. Simultaneously or immediately thereupon the dies 9, 10 clamp the upper part b 110 of the blank the round section of which is

to be preserved and hold it while the punch 29 is actuated to shape the head *c* of the tack. At the next feed of the wire the formed blank comes out of the pressing and 5 clamping dies and finally the cutting dies 20, 21 approach to shape the point and to sever the finished tack from the wire.

I claim—

1. In a machine of the character set forth, 10 the combination of a heading-punch, two holding-dies provided in their working ends with semicircular grooves to clamp the wire beneath the tack-head to be formed, four coöperating pressing-dies to shape a tapering 15 square lower portion of the shank of the tack arranged on one side of the holding-dies, separate cutting-dies for shaping the point of the tack and for severing the tack from the wire arranged on the other 20 side of the holding-dies, and means for feeding the wire.
2. In a machine of the character set forth, 25 the combination of a heading-punch, two holding-dies provided in their working ends with semicircular grooves to clamp the wire beneath the tack-head to be formed, four coöperating pressing-dies to shape a tapering 30 square lower portion of the shank of the tack arranged on one side of and in immediate contact with the holding-dies, separate cutting-dies for shaping the point of the tack and for severing the tack from the wire arranged on the other side of the holding dies, and means for feeding the 35 wire.
3. In a machine of the class described, a heading-punch, a plurality of holding-dies, a plurality of cutting- and point-shaping- dies between the holding-dies and the punch,

a plurality of pressing-dies on the other 40 side of the holding-dies for tapering the lower portion of the shank of the tack, means for operating the cutting- and pointing-dies subsequently to the operation of the other dies.

4. In a machine of the class described, a heading-punch, a plurality of holding-dies, a plurality of cutting- and point-shaping- dies between the holding-dies and the punch, a plurality of pressing-dies on the other side 50 of the holding-dies for tapering the lower portion of the shank of the tack, means for operating the cutting- and pointing-dies subsequently to the operation of the other dies, and means for feeding the wire 55 through the tapering-dies, the holding-dies, and finally through the cutting- and pointing-dies.

5. In a machine of the class described, a heading-punch, a plurality of holding-dies, 60 a plurality of cutting- and point-shaping- dies between the holding-dies and the punch, a plurality of pressing-dies on the other side 65 of the holding-dies for tapering the lower portion of the shank of the tack, and providing said shank with a rectangular cross section, means for operating the cutting- and pointing-dies subsequently to the operation of the other dies, and devices spaced apart 70 to form guides for the holding-dies and serving in part to retain the pressing dies in position.

In testimony whereof I affix my signature in presence of two witnesses.

CARL LEHR.
